UNITED STATES PATENT OFFICE.

HARRY A. DE HART, OF THOROFARxE, NEW JERSEY.

DESIGN FOR A WAGON-BODY.

SPECIFICATION forming part of Design No. 28,703, dated May 24, 1898.

Application filed January 13, 1898. Serial No. 666,575. Term of patent 7 years.

To all whom it may concern:

Be it known that I, HARRY A. DE HART, a citizen of the United States, residing at Thorofare, in the county of Gloucester and State of New Jersey, have invented a certain new and useful Design for a Wagon-Body; and I do declare the following to be a full, clear, and exact description of the invention, such as will enable others skilled in the art to which it appertains to make and use the same, reference being had to the accompanying drawings, and to the figures of reference marked thereon, which form a part of this specification.

Figure 1 is a perspective view of a wagon-body, showing my new design. Fig. 2 is a sectional view taken on the line *x x*.

The leading features of my design consist of a rectangular frame having near its middle a wheel-house and on each side side-boards and seats for tier-boards. In other words, the design is composed of the unitary article shown in the drawings.

1 represents the base-rails; 2, the wheel-house, consisting of ribs 3 and arch 4.

5 represents ribs secured in the base-rails 1 and top rails 6. Said top rails 6 extend inwardly, forming seats 7 or tier-boards 8 to rest on. 9 represents side-boards secured to said top rails. 10 represents basket-boards. 11 30 represents ribs extending from the lower edges of the base-rails 1 up the outer faces of ribs 5 to the lower edges of said boards 9 and thence turning out to the outer edges and under faces of basket-rails 10. 35

12 represents a seat mounted on the front end of the frame, and 13 the foot-rest, secured to the front end of said frame.

Having described my invention, what I claim as new, and desire to secure by Letters 40 Patent, is—

The design for a wagon - body, as herein shown and described.

In testimony whereof I affix my signature in presence of two witnesses.

HARRY A. DE HART.
